KEEPER INSERTING TOOL

Charles A. Dougherty, Wilmington, Del.

Application September 30, 1944, Serial No. 556,589

2 Claims. (Cl. 81—5.1)

1

This invention relates to a tool for inserting the keepers of valve stems.

In internal combustion engines the valves are held under tension by springs which bear against washers slidable on the stem, and the latter telescope split keepers which encircle the stem. The insertion or removal of these keepers is a difficult problem due to the fact that in most vehicles the engines are supported quite low down in the vehicle and the workman must depend upon his sense of feeling in inserting the keepers. An object of this invention is to provide a keeper inserting tool which will render insertion of the keeper certain and easy. Heretofore, tools of this kind have been provided but these prior tools have not found favor with mechanics because of the fact that the keepers were not properly gripped or positioned.

It is, therefore, another object of this invention to provide a keeper inserting tool which will hold the split portions of the keeper in outwardly divergent relation so as to provide for the ready encircling of the stem by the keeper.

A further object of this invention is to provide a tool of this kind embodying a pair of spring-pressed jaws and an intermediate jaw between the pair of jaws, the intermediate jaw being formed with outwardly divergent sides confronting the pair of jaws so as to thereby hold the two parts of the keeper in outwardly divergent relation.

To the foregoing objects, and others which may hereinafter more fully appear, the invention consists of the novel construction, combination and arrangement of parts, as will be more specifically referred to and illustrated in the accompanying drawings; but it is to be understood that changes, variations, and modifications may be resorted to which fall within the scope of the invention as claimed.

In the drawing,

Figure 1 is a plan view, partly broken away and in longitudinal section, of another modification of this invention.

Figure 2 is a fragmentary sectional view taken on the line 2—2 of Figure 1.

Figure 3 is a fragmentary plan view, partly in section, of a modification of this invention.

Figure 4 is a sectional view taken on the line 4—4 of the intermediate jaw removed from the pivoted jaws.

Referring to the drawing, the numerals 73 and 74 designate generally a pair of pivoted handles which are pivotally mounted on a pivot 77. The handles 73 and 74 are elongated and of hollow

construction and are constantly urged apart at their rear ends by means of a spring 78. The handle 73 has secured to the forward end thereof, a jaw member generally designated as 75 and the handle 74 has secured to the forward end thereof, a jaw generally designated as 76. The jaw 75 is of U-shape in transverse section having an upper wall, a lower wall, and a connecting wall or bight. The jaw member 76 is also of U-shaped configuration in transverse section, and is formed of an upper wall, a lower wall and a connecting wall or bight.

The upper wall of the jaw 75 is formed with a concave cutout and the lower wall is also formed with a concave cutout. The outer edge of the cutout in the lower wall is disposed inwardly from the outer edge of the cutout of the upper wall so as to thereby form a seat on which the lower end of one-half of a keeper is adapted to engage. The jaw 76 is also formed with a concave cut-out confronting the cut-out of the jaw 75, the cut-out in the jaw 76 being formed in the upper wall, and the lower wall is formed with a concave cut-out. The outer edge of the lower cut-out is positioned inwardly from the outer edge of the upper cut-out so as to thereby form a second seat on which the other half of the keeper is adapted to engage.

The two handles 73 and 74 are pivotally mounted on a pivot member 77 and the handles are constantly urged away from each other, to thereby normally maintain the jaws 75 and 76 in open position by means of a V-shaped spring 78. The spring 78 in the present form of this invention is bent about the pivot 77 as indicated at 79. An intermediate jaw member generally designated as 80 is slidably mounted on pivot 77 between jaws 75 and 76, and comprises an elongated flat body 81 having an elongated opening or slot 82 extending lengthwise thereof, and within which pivot member 77 loosely engages. The forward end of body 81 has formed integral therewith a substantially V-shaped head or jaw 83 which has inwardly converging opposite sides 84 and 85 confronting the inner portions of jaws 75 and 76. As shown more clearly in Figure 7, the body 81 is substantially thinner than the head or jaw 83 so that this intermediate jaw may be more readily cast to thereby reduce the cost thereof.

Referring now to Figures 3 and 4, there is disclosed a modification of this invention. In this modification the tool comprises a pair of pivoted handles 86 and 87, and a pair of compound jaw members 88 and 89. The handles 86 and 87 are

pivots mounted on pivot member 90 and a U-shaped spring 91 engaging about pivot 90 and extending rearwardly thereof constantly urges handles 86 and 87 apart to normally maintain jaws 88 and 89 in open position.

An intermediate jaw member generally designated as 92 is slidably mounted between the two jaws 88 and 89 and includes a flat body 93 having a substantially V-shaped head or jaw 94 extending from the forward end thereof. The jaw 94 is formed with inwardly converging sides 95 and 96 confronting jaws 88 and 89, and as shown in Figure 4, jaw or head 94 is substantially thicker than body 93. Body 93 is provided with an elongated opening 97 through which pivot member 90 loosely engages so that intermediate jaw 92 may be moved outwardly to keeper retaining position, and may be subsequently moved inwardly to keeper releasing position.

In the use and operation of this keeper inserting tool, the handles 73 and 74 are compressed or moved toward each other thereby opening the jaws 75 and 76. The intermediate jaw 80 is moved forwardly to the limit permitted by the slot 82 and pin 71. At this time, the small end of the jaw formed by the sides 84 and 85 will be disposed adjacent the cut-outs. The complementary portions of the keeper are then inserted in the cut-outs with the open sides thereof confronting each other and with their lower ends resting on the seats. The handles 72 and 73 may then be released so that the spring 78 will expand the handles and contract the jaws 75 and 76, so as to thereby tightly hold the keeper members against the outwardly divergent sides 84 and 85 of the intermediate member 80. The concave end of the intermediate member is then pressed against the periphery of the valve stem and the tool moved forwardly so that the stem will engage between the jaws 75 and 76.

In view of the outwardly divergent position of the two keeper members, the outer edges thereof will initially contact with the stem at substantially diametrically disposed points, and further movement of the tool forwardly will push the intermediate jaw 80 inwardly so that the intermediate jaw 80 will become disengaged from the keeper members 75 and 76 and these members will then encompass the stem. When the keeper members are disengaged from the intermediate jaw 80, the jaws 75 and 76 will tightly clamp these keeper members about the stem and they may be engaged in the conventional annular groove which is formed in the stem to receive these keepers. The tension on the valve springs may now be released so that the valve washer may drop downwardly, and the washer at this time will engage the upwardly projecting portions of the keeper members 75 and 76 so that when the handles 73 and 74 are compressed toward each other to open the jaws 75 and 76, the upper ends of the keeper members will be seated in the keeper socket formed in the valve washer.

While tools of this kind have previously been

constructed, such tools have not found favor with mechanics due to the fact that the keepers were not held in outwardly divergent relation so that they could readily encompass the valve stem as the tool was pushed forwardly. The result of the prior tools was that the keepers would become released or snap out of the jaws and, for this reason, the prior tools have usually been discarded. However, with a tool as hereinbefore 10 described, the keeper members will be firmly held about the stem until the valve washer has been lowered and due to the divergent positioning of the keeper members, prior to and during the insertion operation, the keeper members will 15 readily slide over and about the valve stem and will be retained in encompassing position by the tension of the spring 78.

This application is a continuation in part of my copending application Serial Number 533,879, filed May 3, 1944, for Keeper inserting tool.

20 What is claimed is:

1. A valve keeper inserting tool comprising a pair of pivoted handles, a pair of confronting jaws carried by said handles, said jaws being U-shaped in transverse section and the parallel walls of each jaw having arcuate cutouts with the cutout of one wall of less depth than the cutout of the other wall, and an intermediate jaw 25 within the walls of said pair of jaws and movable lengthwise therebetween, said intermediate jaw having outwardly divergent opposite sides confronting said cutouts whereby to hold semi-circular keeper parts in outwardly divergent relation.
- 30 2. A valve keeper inserting tool comprising a pair of pivoted handles, a pair of confronting jaws carried by said handles, said jaws being U-shaped in transverse section and the parallel walls of each jaw having arcuate cutouts with the cutout 35 of one wall of less depth than the cut-out of the other wall, and an intermediate jaw within the parallel walls of said pair of jaws and movable lengthwise therebetween, said intermediate jaw comprising a body formed with an elongated opening 40 through which the pivot of said handles loosely extends, and a head extending from said body, said head having outwardly divergent opposite sides confronting said jaws and the outer end of said head having a concave recess 45 to engage the peripheral surface of a valve stem.
